LESTER W. COLLINS, OF MODESTO, CALIFORNIA, ASSIGNOR TO ANSUL CHEMICAL COMPANY OF CALIFORNIA, OF MODESTO, CALIFORNIA, A CORPORATION

METHOD OF STERILIZING FRUIT IN REFRIGERATOR CARS

Application filed September 21, 1929. Serial No. 394,297.

This invention relates to the sterilization of fruit, particularly grapes, when they are packed in iced refrigerator cars at the start of the trip to market. My invention also particularly relates to sterilizing by means of sulphur-dioxide gas.

The value of this gas for the above purpose has been recognized for some time, but heretofore it has been considered necessary to open the ventilating hatches of the car while sterilizing operations were in progress to prevent the sulphur dioxide burning the grapes. It has also been considered absolutely necessary to initially dilute the gas with air from outside the car to likewise prevent burning. Retaining the ventilating hatches open, however, requires a much larger volume of gas for sterilizing than would otherwise be the case and seriously interferes with the normal circulation of the air in the cars induced by the ice packed therein. Also, initially diluting the gas requires the use of a very elaborate and expensive apparatus which is very difficult to use in commercial practice. Such an apparatus necessitates a mechanism mounted externally of the car and the use of a false-door, since a main door of the car must be left open to provide for connecting parts of the apparatus disposed both outside and inside the car. Removal of this false-door when sterilizing is completed inevitably permits a considerable quantity of the gas in the car to escape, since the removing operation and the closing of the main door cannot be carried out sufficiently fast to prevent such escape.

The principal object of my invention is to accomplish that which has heretofore been considered impossible or impractical, namely, to discharge the undiluted sterilizing gas into the car in such a manner that it is not necessary to open the ventilating hatches or doors of the car, while at the same time burning of the fruit by the sterilizing gas is positively prevented. I am, therefore, enabled to use a much simpler apparatus which is entirely within the car and which may be instantly placed in or removed from the car upon opening the main door. The quantity

of gas to properly sterilize the fruit is thus greatly lessened since practically none can escape in the outside atmosphere.

Also, the apparatus is of such a nature that a measured supply of sterilizing gas, just sufficient for one car, may be placed in the same, so that there is positively no danger of under or over dosing the fruit, and thus careful supervision of the sterilizing operation is unnecessary.

To illustrate my method the accompanying drawing is presented, which shows in diagrammatic form a fragmentary longitudinal section of a loaded refrigerator car, with the sterilizing apparatus in operation.

In carrying out my sterilizing method I use a tank 1 containing liquefied sulphur dioxide gas, the size of the tank being designed to hold a quantity of the liquefied gas just sufficient for one car, as has been determined by experience. This tank is provided on top with a removably connected spray nozzle 2, the discharge from which is controlled by a suitable valve 3. When the gas is to be discharged the tank 1 is placed in a specially designed vessel 4 which contains water heated to a desired and relatively high temperature. This vessel maintains the tank 1 upright, the nozzle 2 then facing upwardly. By reason of the heated water in the vessel 4 the liquefied gas in the tank 1 is rapidly vaporized and compressed to a high pressure so that when the valve 3 is opened the sterilizing gas is ejected upwardly from the nozzle 4 with considerable velocity.

While the apparatus may be merely set on the car floor during the sterilizing process, when the space between the fruit boxes is sufficiently wide to permit the unobstructed upward passage of the sterilizing gas to the ceiling of the car, and the pressure in the tank is sufficient to carry the gas above the boxes before it commences to spread, yet in practice I prefer to elevate the entire apparatus to a considerable height, preferably above the horizontal central plane of the car or near the topmost boxes of grapes packed therein. The gas as discharged will therefore strike the ceiling of the car

- with considerable force and at a high velocity, the purpose of which will be seen later. It is obvious that the nearer to the ceiling the apparatus is placed, the less pressure in the tank 1 will be required to force the discharged sterilizing gas against the ceiling of the car and hence the less hazardous will be the method to the operator. To thus raise the apparatus to the desired level
- 10 I utilize the horizontal bars of the box bracing 7 as the means upon which to support the apparatus, said bracing usually being in the transverse plane of the doors of the car or centrally of its length. Before the apparatus is set in operation the ice chambers 8 of the car are already filled with ice and a current of air therefore automatically and continuously circulates from the bottom of said chambers, along the car floor
- 15 towards the center and up through the fruit boxes and central box bracing space, then back to the ice chambers in the clear space above the boxes as indicated by the arrows 9.
- The sterilizing gas as discharged from the nozzle 2 striking the ceiling at a high velocity, is spread out and broken up and rolls in cloudlike form along the ceiling and towards the end of the car as indicated at 10. The air currents in the car traveling
- 20 above the fruit boxes in the direction of the ice chambers at each end carry this suspended gas with them, thus causing the gas to travel horizontally much further than it would otherwise do. It is obvious that the
- 25 gas in traveling along the ceiling of the car towards the ice chambers is intimately co-mingled with the car air next the ceiling by the eddy currents and frictional resistance with the ceiling surface and thus
- 30 produces an intimate gaseous mixture relatively dilute with respect to the SO_2 content, and local concentrations which would damage the fruit are thus prevented. However, this gaseous mixture is of a considerably
- 35 greater specific gravity than the air, and consequently tends to settle by gravity, thus passing downwardly through the interstices between the packed fruit boxes and percolates through to the contents of the boxes, as indicated at 11, thus mixing with and displacing the air in such spaces and sterilizing all the grapes throughout the entire car.
- A relatively even distribution of the gas onto the fruit in both directions from the center of the car is thus obtained. Overdosing of the grapes in the boxes nearest the center of the car adjacent to the apparatus is positively prevented by reason of the high velocity at which the sterilizing gas initially strikes the ceiling, and which throws the greater portion of the gas away from the plane of the adjacent boxes before it can drop.
- Also the gas as it is ejected from the nozzle 2 is in a relatively heated condition and
- its specific gravity, and hence its tendency to drop is not as great at the instant it is discharged as after it has been subjected to the cooling influence of the cold air currents continuously flowing from the ice chambers. 70
- As previously stated, the gas tank 1 is of such size that only sufficient liquefied gas is contained therein to properly sterilize a single full car of fruit. Only a few minutes are required for the contents of the tank 1 75 to be discharged into the car, and after this it is a matter of only a few seconds to partially open the car door and withdraw the apparatus from its readily accessible position on the central bracing.
- From the above description it will be seen that I have provided a method which substantially fulfills the objects of the invention as set forth herein and which has been in actual use on many thousands of cars of 80 grapes during the present shipping season.
- Having thus described my invention what I claim as new and useful and desire to secure by Letters Patent is:
1. The method of sterilizing produce in a 85 refrigerator car having an air current circulating lengthwise of the car near the top thereof and induced by the action of the refrigerating means and in which the produce in the car is below such air current, consisting in discharging an undiluted sterilizing gas into the said current whereby said gas will be carried along by and intimately mixed with the air in said current. 90
  2. The method of sterilizing produce in 100 a refrigerator car having a horizontally moving air current through the upper part of the car induced by the refrigerating means in the car and in which the produce in the car is below such current consisting 95 in introducing an undiluted sterilizing gas into the car upwardly from such a level in the car as to cause the gas to flow laterally into the air current whereupon the diffusion of the gas is accomplished essentially 105 through the movement of said current.
  3. In a method of treating produce in a refrigerator car in which there exist free air currents induced by the refrigerating means and moving upwardly through the produce 110 and over the same, the step of introducing undiluted sterilizing gas into the air at the initial point of movement of the air currents over the fruit, whereby the gas is caused to be diffused through said refrigerator car. 115
  4. A method of sterilizing produce in a refrigerator car having an air current circulating lengthwise of the car near the top thereof and induced by the action of the refrigerating means and in which the produce in said car is below such current consisting 120 in effecting the distribution of an undiluted sterilizing gas in the car by disposing within said car a receptacle containing an amount 125

of gas not in excess of that necessary to effectually sterilize the produce within such car and discharging such gas into the current of air whereby said gas will be carried along by and intimately mixed with the air in said current.

5. A method of sterilizing produce in a refrigerator car having air currents induced by the refrigerating means and flowing longitudinally of the car, consisting in discharging an undiluted sterilizing gas into the car in a space at the central portion thereof between piles of containers of produce and in an upward direction, and under pressure so that when discharged the gas will strike the ceiling of the car and be spread out horizontally essentially through the movements of the air currents.

In testimony whereof I affix my signature.
